UNITED STATES PATENT OFFICE.

JOHN VENN AND JOHN ARCHIBALD VENN, OF CAMBRIDGE, ENGLAND.

BOWLING-MACHINE.

913,494.

Specification of Letters Patent Patented Dec. 14, 1909.

Application filed May 20, 1909. Serial No. 497,318.

To all whom it may concern:

Be it known that we, JOHN VENN, F. R. S., of Vicarsbrook, Chaucer Road, Cambridge, England, and JOHN ARCHIBALD VENN, B. A., of 10 Brookside, Cambridge, England, have invented an Improved Bowling-Machine, of which the following is the specification.

This invention relates to an improved bowling machine.

10 The object of the invention is the production of a machine of simple construction upon a new method or system of working, that shall firstly, be capable of projecting a ball at a wicket or the like, or at any desired point on either side of the wicket or the like, with accuracy, and at any desired or adjusted velocity and length of pitch, and secondly and more especially, the combination of such an apparatus or device with the machine, that shall enable the machine to deliver the ball with a break in any desired direction, that is, with any adjusted or desired degree of rotation or spin about an axis in any direction.

25 We provide our machine with a suitable base or support formed of any suitable material, and we anchor the said base or support by means of a suitable pin or metallic stake or the like, secured in the ground. 30 The said pin or metallic stake or the like is secured to the base or support at one end in such a manner that the machine may be pivoted thereon so as to alter the direction of discharge of the ball.

35 Pivoted upon the said base or support in such a manner as to be capable of a forward and backward movement, is the throwing or catapult arm of the machine. This is adapted to slide easily in a guide, which guide 40 may be formed as a slot in the upper framework of the machine if it be formed of suitable metal, such as a casting, or the said guide may be formed of two bars or rods fixed longitudinally of the machine.

45 Secured at the forward end of the machine in a suitable position is a spring, the other end of which is secured to the throwing arm. This spring is preferably a tension spring, but if a spring in compression 50 be employed, then the spring or springs, for two or more springs may be employed are preferably placed behind the throwing arm. The said throwing arm may be either formed of metallic tube, such as steel, or it 55 may be made of a light, tough wood of rectangular section. On a rod or tube at the

top or outer end of the throwing arm is mounted a clutch which carries the ball. The clutch is adapted to release the ball at the desired moment. At a certain position in the stroke, and adapted to be adjusted so as to shorten or lengthen the stroke of the throwing arm, we may provide a pneumatic stop, or spring buffer or the like, suitably constructed to perform its office. This stop or buffer or the like serves to receive the impact of the throwing arm. We prefer to fit the spring buffer as a tension spring.

Referring to the before mentioned clutch. This is so constructed in a suitable manner, that it shall, while gripping the ball, communicate to it a rotation about an axis in the desired direction. And the clutch may be constructed for example as follows:— Two or more levers are formed all having 70 their fulcrums mounted upon one disk, which fulcrums are situate at the upper end of the throwing arm. The longer arms of the said levers extending from the fulcrums may be formed each as a segment of a circle in 75 order to embrace the ball. At the moment of throwing, the lever arms are caused to fly open and so release the ball.

We mount the clutch spindles or spindle on ball bearings, a spindle having a small 80 pulley or its equivalent on its one end, and a fork or its equivalent for gripping the ball on the other. One equivalent of the fork is a cup which may be deep or shallow. The 85 said fork or its equivalent may be pressed by a spring placed on the lever. A spring or 90 springs may be used in a suitable manner in order to exert pressure upon the ball to hold it, but preferably the spring or springs are released at the moment of throwing, and this 95 release, releases the ball. Any system of operating the said levers for releasing and the like may be adopted. A cam is mentioned in our provisional specification for releasing the lever, but we prefer to release the said 100 levers which are employed to hold the ball, in one constructional form, by means of a disk. The said pulley may be rotated in any convenient manner, but one method for example, is that of winding a cord around 105 same which may be pulled off the pulley at the moment of impulsion or stopping of the throwing arm. Reducing gear may be employed to extend the springs or compress same for propulsion of the throwing arm. 110 And in order that our invention may be completely understood, reference should be

made to the accompanying drawings of which—

Figure 1 is an elevation of the ball throwing apparatus. Fig. 2 is a plan of the apparatus. Fig. 3 shows one constructional form of ball carrying and spring clutch in part section. This clutch is employed for giving rotation to the ball about an axis in any direction. Fig. 4 shows another constructional form of clutch in plan. This clutch is for giving a spin to the ball about a horizontal axis at right angles to the line of flight. Fig. 5 shows in elevation and part section a simpler form of clutch for delivering the ball spinning about an axis coincident or approximately so with the direction of flight. Fig. 6 is an end view of same, and Fig. 7 is a plan of same. Figs. 8 and 9 are views of the universal joint employed to 20 carry the clutches shown in Figs. 3 and 4.

Like letters of reference refer to like parts in all the figures.

Referring to Figs. 1 and 2, A is the base or support of the apparatus.

B is the hole through which the metallic stake or pin is driven into the ground to secure the frame longitudinally. The frame may be turned to a certain extent upon the said pin as a pivot, so as to alter the direction of discharge of the ball. The slot C in the front of the frame allows of this adjustment. The metallic stake or pin employed in the front of the frame is placed through this slot, the slot permitting of the lateral movement of the frame. The bar F is hinged at G to the base A. This enables the throwing arm D and a portion of the frame to be raised at the front end in order to alter the trajectory of the ball thrown. The frame is supported when raised upon the cross bars of the hinged rack H. The height of the frame may be adjusted by placing it in another hole of the adjustable or support rack H.

The throwing arm D is pivoted on the pin I mounted on the bar F. It is connected to the front bar J of the frame by the spring K. It is also connected to the back bar L of the frame by the cord M. The cord M is secured at the other end to the buffer spring N.

O O, are guide bars, one on each side of the throwing arm D, to prevent any undue lateral movement of the throwing arm.

F¹ F², are bars to more firmly secure the end members J, L, of the frame to the lower bar F. The clutch carrier D¹, which may be a flat or round rod of any suitable material is secured to the top of the throwing arm D, by means of set screws, and its position is adjustable. The clutch P is secured to the carrier D¹ by means of the adjustable joint D², which permits of adjusting or setting the clutch P at a different vertical angle with the carrier D¹, and at the same time

allows said clutch to be swung laterally. The clutch P is shown to a larger scale in Fig. 3.

The string, wire or cord D⁵ is employed to release the clutch P as hereafter described. The cord D⁵ is connected at its lower end to the back frame member F¹, it passes behind the eye D³ and thence through the center of the hollow rod P¹ to release the clutch. The cord D⁵ becomes taut when the throwing arm D is near the end of its stroke, and so exerting a pull on the clutch mechanism releases the ball.

The dotted lines Fig. 1 indicate the other position of the throwing arm D. When drawn back to this position extending the spring K, the catch or hook D⁴, is placed behind the pin or eye D³, to hold it in this position. The clutch P is then adjusted to the desired position for throwing. The clutch P which is mounted on ball bearings on the rod P¹ is then rotated in whichever direction it may be desired to spin the ball. This is preferably done by means of a small pulley fixed to the spindle such as shown P², Figs. 3, 5, 6 and 7. A piece of string or the like is wound around the pulley and being pulled in unwinding rotates the clutch and ball at a good speed. The catch or hook D⁴ is then released by hand. The spring K pulls the throwing arm D sharply forward, and when near the end of its stroke, the clutch P releases the ball Q, which is thus thrown spinning at the wicket or desired mark, which mark may be a spot on either side of or in front of the wicket or the like.

Referring to Fig. 3, the ball Q is held by the four levers of which P³, P⁴, P⁵ only appear in this view. The said four levers are mounted on fulcrum pins on the disk or end flange of the sleeve P⁷, which sleeve is adapted to rotate freely on ball bearings on the solid continuation of the rod or spindle P¹. Each lever is provided with a spring as shown on the lever P³, which tends to open outwardly the lever and release the ball, that is to say to place the levers radially to the rod P¹. The pulley P² in this figure serves another and additional purpose beside that of receiving the string used for spinning the ball. The pulley P² is mounted to slide longitudinally on the sleeve P⁷. The flange of the pulley P² is pressed forward assisted by the action of the spring P⁸ and is so placed that the shorter arms of the levers P³, P⁴, P⁵ and P⁶ (the latter not shown) rest upon its edge. The longer arms of the levers are thus pressed against the ball Q to hold it. In order that the pulley P² may be slid backwardly so as to release the levers and ball, and yet be permitted to rotate freely, the pulley is provided with a ring ball bearing P⁹ having fitted thereto the wire connection P¹⁰. The wire P¹⁰ is

passed through a slot made in the hollow rod P^1 , and the string or cord D^5 is secured to the wire inside the hollow rod. When the string is pulled, the four levers are released and fly open by the action of their springs so releasing the ball.

Referring to Fig. 4, the ball Q is held between two shallow cups R R^1 . These cups are rigidly fixed to spindles which carry the pulleys P^7 P^7 at their other ends. The said spindles are mounted on ball bearings fitted within the tubes R^2 R^3 , to allow of free rotation of the cups and ball. The tubes are carried by brackets as shown fixed to the sliding sleeves R^4 R^5 . The said sliding sleeves R^4 R^5 also carry the pins R^6 R^7 respectively. These pass through slots in the inner fixed tubes R^8 R^9 respectively. The length of the slots shown dotted, determine the degree of movement permitted to the sleeves upon the said inner fixed tubes R^7 R^8 . Within each of the said inner tubes R^7 R^8 is fitted a spring, one end of which is secured in the tube end, and the other to the said pins. Consequently the said pins, and therefore the sleeves and cups connected thereto are always pulled outwardly by the said springs. In order to hold the cups pressed against the ball in opposition to the tension of the said springs, the double hook or detent R^{10} is provided. The double hook or detent R^{10} is adapted to slide upon the hollow rod P^1 . When the cups R R^1 are pressed together into contact with the cup to hold same, the detent R^{10} is pressed forward so that the two hooks thereon engage and hold the pins R^6 R^7 . When the clutch is in position on the throwing arm, it will be seen that if the cord D^5 is pulled, the detent R^{10} to which the cord is secured in being drawn backwardly the hooks release the pins R^6 R^7 . The cups consequently by the action of the springs within the tubes R^7 R^8 immediately release the ball.

Referring to Figs. 5, 6, and 7. In this constructional form of clutch, there is but one cup S , which is deeper, so that the ball is just a holding fit by friction, slight pressure being used to press the ball Q into the cup S . The clip S^1 provided with the set screw S^2 serves to secure the clutch to the said rod. The cup S is fixed to one end of a spindle S^3 , which spindle is mounted on ball bearings within the tube or sleeve S^4 . In this modified form of clutch when the pulley P^2 , and therefore the clutch and ball have been rotated by the string as before described, and the throwing arm has been released by means of the catch D^4 , the impact when the arm is stopped by the buffer spring X is sufficient to release the ball Q from the cup S , by overcoming the frictional hold of the ball.

Referring to Figs. 8 and 9, W is the clamp for fitting over the top of the throwing arm

D , and D^4 is the rod fixed thereto. W^1 is the hole through which the rod P^1 of the clutch is fitted. When it is in position the fly nut is tightened up and the rod is clamped against the shoulder W^2 to fix it when adjusted in the desired position. W^1 forms the head of the bolt of the flynut W^2 . To obtain adjustment in a direction at right angles thereto, the rod D^4 fits in the clamp hole W^4 .

What we claim as our invention and desire to secure by Letters Patent is:—

1. In a ball throwing machine, a base, a framework mounted on the base, a throwing arm hinged to the framework, a clutch on the free end of said throwing arm, and flexible means for releasing the ball from the clutch at a predetermined instant said flexible means being drawn taut and releasing the clutch when said throwing arm has traveled a certain distance.

2. In a ball throwing machine, a base, a framework mounted on the base, a throwing arm hinged to the framework, a ball-holding device on the free end of said throwing arm, said ball-holding device so connected to said throwing arm as to be pivotally adjustable vertically and laterally, and means for releasing the ball from said ball-holding device.

3. In a ball throwing machine, a base, a lever member hinged to the base, a throwing arm hinged to said lever member, springs for setting said throwing arm in motion, a ball-holding device on the free end of said throwing arm, means for automatically releasing the ball from said holding device, and means for rotating said device before the ball is released.

4. In a ball throwing machine, a base, a lever member hinged to the base, a throwing arm hinged to said lever member, guide-ways for said throwing arm, said guide-ways extending longitudinally of said base, a catch for holding the throwing arm at the rear end of the guide-way, and means for moving said throwing arm to the other end of the guide way, when the catch is released.

5. In a ball throwing machine, a base, a lever member hinged to the base, means for adjusting one end of said lever member in various positions, a throwing arm hinged to said lever member, guide-ways for said throwing arm, a catch for holding the throwing arm at the rear end of the guide-way, and means for moving said throwing arm to the other end of the guide-way when the catch is released.

6. In a ball throwing machine, a base, a lever member hinged to the base, a throwing arm hinged to said lever member, standards on said lever member, guide-ways for said throwing arm mounted on said standards, a catch for holding the throwing arm at the rear end of the guide-way, and means

for moving said throwing arm to the other end of the guide-way when the catch is released.

7. In a ball throwing machine, a base, a framework on the base, a throwing arm hinged to the framework, a ball-holding device on the free end of said throwing arm, said ball-holding device comprising a revoluble holder, a pulley connected with the holder and adapted to be rotated and means for releasing the ball from said holder, and means for operating said throwing arm.

8. In a ball throwing machine, a base, a framework on the base, a throwing arm

hinged to the framework, a ball holding device on the free end of said throwing arm, said ball-holding device comprising a spindle, a clutch connected thereto, a pulley on said spindle adapted to be rotated, means connected with said clutch adapted to release the ball at a predetermined instant and means for operating the throwing arm.
